UNITED STATES PATENT OFFICE.

HENRY B. LEVY, OF NEW YORK, N. Y.

POCKET-CLIP FOR FOUNTAIN-PENS.

No. 845,467.

Specification of Letters Patent.

Patented Feb. 26, 1907.

Application filed December 1, 1906. Serial No. 345,894.

To all whom it may concern:

Be it known that I, HENRY B. LEVY, a citizen of the United States, residing at New York city, Manhattan borough, county and State of New York, have invented certain new and useful Improvements in Pocket-Clips for Fountain-Pens, of which the following is a clear, full, and exact description.

This invention relates to pocket-clips for fountain-pens, pen-holders, pencils, and the like, the object being to provide a cheap and effective fastening device which can be attached to the cap of a fountain-pen or the like for the purpose of detachably holding the same in a pocket.

To these and other ends, which will hereinafter appear, my invention comprises the novel features of improvement which I will now proceed to describe and finally claim, reference being had to the accompanying drawings, forming part of this specification, wherein—

Figure 1 illustrates an elevation of a fountain-pen with my improved clip attached to the cap thereof. Fig. 2 is an enlarged vertical sectional view of a fountain-pen cap having my improved clip attached thereto, the section being taken on a line *a a* in Fig. 1, a portion of the barrel being shown in elevation. Fig. 3 is an enlarged cross-sectional plan view, the section being taken on a line *b b* in Fig. 2; and Fig. 4 is an enlarged detail perspective view of my improved clip.

Like numerals of reference are intended to indicate corresponding parts in the several views.

Referring to the drawings, the numeral 1 indicates the cap of a fountain-pen; to which is attached my improved clip 2. 3 indicates the usual opening or vent in said cap. I utilize the said opening 3 for the purpose of preventing longitudinal displacement of the clip 2, and I may or may not increase the size of said opening 3 over that usually used.

As will be seen by Fig. 4, the clip 2 is composed of the curved retaining-wings 4 and 5, which are designed to slip over the cap of the fountain-pen freely and need not have any spring or grasping action to prevent the clip from being displaced from the cap by any side thrust or pressure, and my said clip is also provided with a grasping or spring finger 6, which is designed to exert sufficient

pressure upon that part of the pocket or clothing which is inserted at point 7, Fig. 2, between said finger 6 and cap 1. To prevent the clip from being displaced longitudinally I provide a retaining-arm 8, which is preferably slightly resilient, said arm being provided with an inwardly-projecting nose 9, which is adapted to pass through the air vent or opening 3 of cap 1.

As will be seen by Fig. 3, said nose 9 is approximately the width of the opening 3, but not thick enough to completely fill said opening, (see Fig. 1,) so as to destroy its utility. The wings 4 and 5 are preferably diamond-shaped and almost surround the cap, leaving a gap 10 opposite to the bridge portion 11 of the clip 2. The diamond shape of the wings causes them to be resilient to an extent sufficient to aid the finger 6 to perform its function of grasping the clothing, at the same time making it much easier to fit the pen-cap than if the said wings were rectangular, as there is less liability to twist. To place the clip on the cap, it is but necessary to slip the wings 4 and 5 over the cap, pressing the arm 8 outwardly until the nose 9 has been brought opposite to the opening 3, at which point said nose can be allowed to spring in. By this mode of fastening the clip in position a firm and effective clip is produced, and as same is made of an integral piece of sheet metal the entire device can be stamped out and shaped at little cost. It will of course be understood that the nose 9 need not pass entirely through an opening, such as 3, but may enter a notch or recess in the cap or pencil to which it is applied.

Having now described my invention, what I claim, and desire to secure by Letters Patent, is—

1. In combination with a fountain-pen cap provided with an opening, of a clip, and means carried by said clip adapted to engage said opening.
2. In combination with a fountain-pen cap provided with an opening, of a clip, wings carried by said clip and adapted to partly surround said cap, an arm, and a projection carried by said arm adapted to engage said opening.

HENRY B. LEVY.
